UNITED STATES PATENT OFFICE.

THOMAS R. STURGEON, OF NEW YORK, N. Y.

SPEED-CHANGE DEVICE.

1,374,614.

Specification of Letters Patent. Patented Apr. 12, 1921.

Application filed October 2, 1919. Serial No. 327,991.

To all whom it may concern:

Be it known that I, THOMAS R. STURGEON, a subject of the King of Great Britain, and a resident of the city, county, and State of New York, (whose post-office address is % Chas. Butters & Co., Ltd., 90 West street, New York city,) have invented certain new and useful Improvements in Speed-Change Devices, of which the following is a specification.

My invention relates to a speed reduction device and has special application to differential arrangements used for the purpose of transmitting rotary motion from one member to another.

It was an object in designing apparatus embodying my invention to simplify the same, to remove all toothed gearing therefrom, to eliminate friction as much as possible, to provide an arrangement whereby the driving and driven members are concentric, at the same time producing a structure which is simple and compact, and balanced so as to eliminate vibration.

The following is a description of an embodiment of my invention and will be better understood by referring to the accompanying drawings forming a part thereof, and in which—

Figure 1 is a sectional elevation of one form of the apparatus;

Fig. 2 is a section on line 2—2 of Fig. 1;

Fig. 3 is a section on line 3—3 of Fig. 1;

Fig. 4 is a detail of the eccentric;

Fig. 5 is a sectional elevation of another embodiment of my invention;

Figs. 6, 7 and 8 are details of the coupling means;

Fig. 9 is a diagram; and

Fig. 10 shows another embodiment of the invention.

Referring to Fig. 1, the apparatus consists of a bed plate 1 carrying a bearing block 2 for the driven shaft 3. Mounted on the bed plate 1 is a member 4, which supports a bearing 5 for the driving shaft 6. The member 4 has an upright part 7. Mounted also on the bed plate 1 is an upright member 8 parallel with the member 7. Mounted between the members 7 and 8 are a plurality of rollers 9, 10, 11 and 12, there being four in this particular structure. Each of the rollers has a shaft journaled one end

in the member 7 and the other end in the member 8. These four rollers are equally spaced on their circular center line, and in this structure have centers 90 degrees apart and are concentric with the shaft 6.

Mounted on the shaft 6 and rigid therewith is an eccentric 13 and mounted on the eccentric 13 is a cam 14. Also mounted on the shaft 6 is a counterbalance 13' for the purpose of balancing said shaft. One end of the cam 14 has three projections 15, 16 and 17 and the other end has two projections 18 and 19. The contacting surfaces of the cam are in the form of substantial arcs of circles.

Mounted parallel to the members 7 and 8 are two members 20 and 21, which members 20 and 21, however, are free from the bed plate 1, and as will appear later, revolve around concentric with the shafts 3 and 6. Mounted between the members 20 and 21 are three rollers 22, 23 and 24, each having a shaft journaled one end in the member 20 and the other end in the member 21. The member 20 has an opening in the center thereof sufficient to allow for the movement of the cam 14. The member 8 also has such an opening. The member 21 is rigidly fastened to the driven shaft 3 and drives the same. It will be noted that the shaft 6 extends into a central opening in the end of the shaft 3, which opening forms a bearing for the shaft 6. The cam 14 is so mounted on the eccentric 13 that it may rotate with respect thereto.

The operation of the device above described is as follows:

The shaft 6 being the driving member, upon being rotated operates the eccentric 13, which in turn operates the cam 14, which cam has a double motion, to wit an eccentric motion corresponding to that of the eccentric 13 and a rotary motion by reason of its engagement with the rollers 9—12. While each of the rollers 9—12 is arranged to rotate about its axis it is, nevertheless, fixed in the members 7 and 8 relative to the bed plate; therefore, as the projections 15, 16, and 17 on one end of the cam 14 engage the rollers, the cam is given a rotative movement around the eccentric 13, and in fact rotates in a direction opposite the rotation of the shaft 6. The cam 14 being rigid through-

out, the projections 18 and 19 engaging the rollers 22, 23 and 24 cause the members 20 and 21, which are fastened together and which carry the rollers 22, 23 and 24, to rotate and in so doing, to drive the shaft 3 in the bearing 2, the relative speeds of the shafts 6 and 3 being dependent upon the number of rollers employed. The speed ratio may be arrived at by the use of the following formula:

$$\text{Ratio} = X(Y-1) \text{ to } 1$$

where Y equals the number of rollers in the fixed set and X equals the number of rollers in the movable set. It is also true that when X is equal to or less than $Y-1$, the drive is positive, that is to say, the shaft 6 and 3 rotate in the same direction but at different speeds, while X is greater than $Y-1$, the drive is negative, that is to say, the shaft 3 rotates in a direction opposite to that of shaft 6 and at a speed dependent upon the number of rollers employed. The number of projections on the end of the cam 14 is always one less than the number of rollers engaged by that end.

From the foregoing it will be apparent that by varying the number of rollers of the two sets, certain ratios can be obtained, that is to say, certain ratios give a positive drive and certain other ratios give a negative drive.

While the frame containing the rollers 9-12 has been described as being fixed to the bed plate 1, it is obvious that this frame might be arranged so that it might revolve and its speed of revolution controlled thereby varying the speed of shaft 3 or stopping it altogether while shaft 6 continues to revolve; or the power may be applied to this frame and the shafts 3 and 6 rotated at the same or different speeds as in the well known automobile differential.

The modification shown in Fig. 5 is the same as that of Fig. 1 except the second set of rollers, to wit the rollers 22, 23 and 24 have been omitted together with the members 20 and 21. The power is transmitted in that arrangement from the shaft 6 to the shaft 3 through the cam 14, rollers 9-12 as in Fig. 1, and then through an Oldham coupling, so that the speed of the shaft 3 is the same as the speed of rotation of the cam 14, which speed is determined by the number 55 of rollers corresponding to those numbered 9-12; that is to say, in the example shown, there being four rollers, the speed of rotation of the cam 14 would be three to one in a direction opposite to the rotation of the shaft 6, and therefore, would be a negative drive. The coupling shown in detail in Figs. 6, 7 and 8 comprises a member 25 rigidly connected with the cam 14, in fact integral therewith. There is also a member 65 26 which has thereon a feather or projec-

tion 28, which works in a corresponding slot 27 in the member 25. There is also a member 29 rigidly connected with the shaft 3. This member 29 has a slot 30 therein which receives a projection 31 on the member 26, 70 which projection 31 is at right angles to the feather 28. By this arrangement the shaft 3 receives a constant angular velocity, the same being determined by the speed ratio of the reduction device as above specified. 75

By the modification of the invention shown in Fig. 5 any desired ratio consisting of a whole number from 2 to 1 upward may be obtained. It is noted also that by this modification nothing but a negative drive 80 can be produced. The ratio of the speed reduction would be as the number of rollers minus one is to one.

The following is the correct method of arriving at the proportions of the engaging 85 surfaces so as to give to the driving member a constant angular velocity.

In Fig. 9 the diameter of circle B is equal to the diameter of the circular path followed by the eccentric 13, which gives to the cam 90 14 the same bodily circular travel. The diameter of circle A is equal to the diameter of circle B multiplied by the number of rollers in the set considered. Points E equally divided circle A into parts equal in number 95 to the number of rollers in the set. When circle B is midway between two of these points E, an arc which will pass through two points E and will also touch circle B at point C (point C bisecting the arc) will define the radius FE which will be equal to FC. A circle J struck from the same center as circle A and passing through point F represents the roller circle. Fig. 9 is drawn for four rollers and points F represent their 100 centers.

The radius of the rollers G may be anything less than the radius FE which is suitable for required strength and convenience in manufacture. 110

The portion H of the cam, which touches the roller G will closely approximate to an arc of a circle and will be of such form as will give a uniform angular velocity to the drive member. The number of parts H will 115 be one less than the number of rollers in the set considered.

Fig. 10 shows an arrangement in which both frames carrying the rollers or other bearing surfaces 9, 10, 11, 12, 22, 23 and 24, 120 are free from the bed plate 1. One of these frames, as 7-8, may be driven by motor 32 through a belt 33 or other suitable means. The two frames 7-8 and 20-21 are mounted on a single shaft 34 and are free 125 to rotate thereon. This shaft 34 is provided with an eccentric corresponding to the eccentric 13 of Fig. 1 and also with the cam 14, as in the other figures. The frame 21 drives a pulley 35 by means of a belt 36 or 130

other suitable means. By using my invention in the embodiment of Fig. 10 the motor 32 drives a shaft 37 at a speed change in accordance with the following formula:

$$5 \quad \text{Ratio} = \frac{Y}{Y-1} \times \frac{X-1}{X} \text{ to } 1;$$

Y=number of rollers in driving set and X=number of rollers in driven set, and the 10 drive is always positive. In the apparatus shown in the drawings, if the frame 7-8 is driven, the speed ratio between the frames 7-8 and 20-21 would be eight-ninths.

From the foregoing it will be seen that 15 the embodiments of my invention are extremely simple, are rugged and compact, and that friction is reduced to a minimum.

It is obvious that if found desirable, ball-bearings may be provided at any desired 20 point such as, for instance, between the eccentric 13 and cam 14.

It is obvious also that instead of rollers 25 9-12 and 22-24, fixed surfaces of the proper configuration might be used without departing from the spirit of my invention, although I prefer to use rollers on account of the fact that they tend to eliminate friction between the bearing surfaces.

Having described my invention, what I 30 claim as new and desire to secure by Letters Patent is:

1. In a speed change device, the combination of a driving member, a double cam having projections in the form of substantial 35 arcs of circles on each end thereof and operated by said member, a plurality of stationary rollers engaged by one end of said cam and a plurality of rollers on a driven member operated by the other end of said cam.

2. In a speed change device, the combination of a driving member, a cam having uniform projections in the form of substantial arcs of circles thereon operated thereby, stationary rollers engaged by one end of said cam and a different number of movable rollers engaged by the other end of said cam.

3. In a speed change device, the combination of a driving and a concentric driven 50 member, a set of rollers connected with the driven member, a fixed set of rollers and means including a cam having a different number of projections in the form of substantial arcs of circles on the ends thereof engaging said sets of rollers for driving said driven member at a different speed from that of said driving member.

4. In a speed change device, the combination of a driving member, a double ended 60 cam loosely mounted on said member, projections in the form of substantial arcs of circles on each end of said cam, a fixed member engaged by one end of said cam whereby the speed of the cam is reduced relatively to 65 that of the driving member, a member en-

gaged by the other end of the cam whereby it is driven at a reduced speed relatively to the cam.

5. In a speed change device, the combination of a driving and a concentric driven member, speed reducing means connecting said members and comprising a double ended cam operated by said driving member and rotatable relative thereto, a set of rollers engaged by one end of said cam and controlling the rotation thereof, and a second set of rollers engaged by said cam and rotated thereby, the contacting surfaces of the cam being substantially arcs of circles. 70 75

6. In a speed change device, the combination of a driving member and a concentric driven member, speed reducing means connecting said members comprising a fixed and a movable set of rollers and a rotating double ended cam engaging said rollers and operated by said driving member, the contacting surfaces of the cam being substantially arcs of circles. 80 85

7. In a speed change device, the combination of a driving member and a driven member, a double ended cam, means on the driving member for operating the cam, a fixed frame, means in said frame engaging with said cam to give said cam a rotative movement relative to said driving member, and a rotatable frame connected to said driven member and operated by said cam, the contacting surfaces of the cam being substantially arcs of circles. 90 95

8. In a speed change device, the combination of a driving member, a double cam operated by said member, a plurality of rollers engaged by one end of said cam and a plurality of rollers on a driven member operated by the other end of said cam, the contacting surfaces of the cam being substantially arcs of circles. 100 105

9. In a speed change device, the combination of a driving member, a cam having uniform projections thereon operated thereby, 110 rollers engaged by one end of said cam and a different number of rollers engaged by the other end of said cam, the contacting surfaces of the cam being substantially arcs of circles. 115

10. In a speed change device, the combination of a double cam having a plurality of projections on each end, a frame having a plurality of circular surfaces therein for engagement with the projections on one end 120 of said cam, a second frame with a plurality of circular surfaces therein for engagement with the other end of said cam, and means for driving one of said frames.

11. In a speed change device, the combination of a driving member, a driven member with a bearing supporting one end of said driving member, a cam eccentrically mounted and rotatable on said driving member, each end of said cam consisting of an in- 125 130

tegral symmetrical plurality of curves substantially the same as arcs of circles and differing in number one end from the other, a fixed set of rollers engaged by one end of 5 said cam and controlling the rotation thereof, a movable set of rollers on said driven member engaged by the other end of said cam, the number of rollers in each set being one more than the number of curves on said 10 cam engaged thereby, said sets of rollers and driving and driven members being concentric.

12. In a speed change device, the combination of a driving member, a concentric driven 15 member with a bearing supporting one end

of said driving member, a cam eccentrically mounted and rotatable on said driving member, said cam having integral with it a symmetrical plurality of curves substantially the same as arcs of circles, a fixed set of rollers 20 concentric with said driving member and numbering one more than the curves on said cam and controlling the rotation thereof, means for transmitting the rotation of said eccentrically mounted cam to said concentric 25 driven member.

In testimony whereof, I have signed my name to this specification.

THOMAS R. STURGEON.
